UNITED STATES PATENT OFFICE.

GEORGE ENTWISTLE, OF JERSEY CITY, NEW JERSEY.

PAIL.

1,210,284.

Specification of Letters Patent. Patented Dec. 26, 1916.

Application filed February 2, 1916. Serial No. 75,887.

To all whom it may concern:

Be it known that I, GEORGE ENTWISTLE, a citizen of the United States, residing at Jersey City, in the county of Hudson and State of New Jersey, have invented new and useful Improvements in Pails, of which the following is a specification.

The present invention relates to improvements in receptacles and has relation more particularly to a closure therefor.

The primary object of the invention is the provision of a closure so constructed as to permit of the cover being used on receptacles of various sizes.

A still further object of the invention is the provision of a cover of the above stated character embodying a plurality of loosely assembled lapped segmental sections, and means passing through the sections for permitting the sections to be expanded or contracted whereby the cover will be adaptable for receptacles of various sizes.

With the above and other objects in view, the invention consists in the novel features, details of construction and combination of parts which will hereinafter be more fully set forth, illustrated in the accompanying drawing and pointed out in the appended claims.

In the drawings: Figure 1 is a perspective view showing the cover in applied position; Fig. 2 is a bottom plan view of the receptacle to which the cover is attached; and Fig. 3 is a vertical section taken through the receptacle and cover.

Referring more particularly to the drawing, 5 denotes a receptacle which is preferably constructed of sheet metal and the like material having a body portion 6 having adjacent the lower edge thereof an inwardly extending concentric flange 7. Co-operating with the flange 7 of the receptacle is a spring actuated bottom 8 constituting separable leaves 9 and 10 pivotally connected with the receptacle and to one another by means of a pintle 11. The body portion 6 of the receptacle at points below its inwardly extending flange 7 is further provided with a concentric stamped groove 12 for accommodating a pair of diametrically opposite flat springs 13 and 14, such springs being permanently secured to the exterior face of the leaves by means of fasteners 15. In order that the contents of the receptacle may be conveniently discharged therefrom I provide an improved means for

dumping the bottom 8 which comprises an actuating rod 16 journaled in the walls of the receptacle 5 at a point below and in spaced parallel relation with the pintle pins 11 and provided with lateral extensions 17. The operating rod 16 is operatively connected with the flat springs 13 through the medium of links 18 connected at one end to the springs and connected at the opposite ends with the lateral extensions 17 and the actuating rod 16 is rocked through the medium of an operating hammer 19 which extends upwardly and in spaced relation with the exterior surface of the body portion 6 of the receptacle.

It will, of course, be understood that the receptacle as shown is merely illustrative inasmuch as the essential features of my invention embody an improved closure 20 so constructed as to permit of the same being employed on receptacles of various diameters. The closure 20 is preferably constructed of sheet metal material and embodies a main disk 21 having a centrally located opening 22, the walls 23 of such opening being formed with a concentrically arranged slot 24 for detachably connecting with the walls 23 an auxiliary disk 25, through the medium of a fastener 26, the fastener 26 extending through the slot 24 and permanently retaining the auxiliary disk 25 above and in spaced relation with the main disk 21 for a purpose which will hereinafter be more fully explained. The auxiliary disk 25 is provided with a plurality of relatively spaced radially extending slots 27 for slidably receiving the studs 28 of an expandable and contractible rim 29. The rim 29 comprises a series of segmental sections 30, each section underlapping the adjacent section on one side and overlapping its adjacent section on the other side which will readily permit of the adjustment of the sections to adapt the same for receptacles of various diameters and furthermore assures a tight connection of the closure with such receptacle. The studs 28 which project through the slots 27 are threadedly connected in the apertures 31 of each of the segmental sections 30 at points adjacent the inner end thereof, while the opposite end of each of the segmental sections 30 is bent inwardly as at 32 to provide a flange 33 of substantially U-shaped configuration in cross section and adapted to ride over the flanged top 34 of the receptacle 5. The outermost

limb 35 of the U-shaped flange 33 is formed with a depending loop 36 and passing through the loops 36 is an adjusting ring 37 which through the medium of the adjustment of such ring causes movement of the studs 28 in the slots 27 and expands or contracts the segmental sections as the occasion may so demand. The cover 20 is fastened to the receptacle 5 through the medium of 10 adjusting screws 38. The opening 22 of the main disk 21 is closed by means of a spring actuated lid 39 and is hinged to the wall 23 of said opening. It is obvious from the drawing that in assembling the various sections constituting the adjustable cover 20 each of the segmental sections is inserted within the space 40 formed by the main and auxiliary disks 21 and 25 respectively and it is to be further stated that any number 20 of such sections may be employed as is found necessary in the practical use of the device.

From the foregoing description, taken in connection with the accompanying drawing, the advantages of construction and of the method of operation will be readily apparent to those skilled in the art to which the invention relates, and while I have described the principles of operation of the 30 device together with the device which I now consider to be the best embodiment thereof, I desire to have it understood that the device shown is merely illustrative and that such changes may be made when desired 35 as are within the scope of the claims appended thereto.

I claim:

1. A closure for receptacles providing a main disk having a central opening, the 40 walls forming the opening being slotted, an auxiliary disk, means carried by said auxiliary disk and extending through the said slots for connecting the auxiliary disk in spaced relation with the former mentioned 45 disk, and a plurality of loosely assembled lapped segmental sections interposed be-

tween the main and auxiliary disks and capable of expansion and contraction.

2. In combination with a receptacle having a flanged top, of a closure therefor, said closure embodying a plurality of loosely assembled lapped segmental sections, said sections being formed at their outer ends with a flange adapted to receive the flange of the receptacle, loops carried by said segmental sections, and means extending through said loops for permitting of the expansion or contraction of the segmental sections.

3. A closure for receptacles embodying a main disk, an auxiliary disk arranged above and in spaced relation with the main disk and detachably connected thereto and provided with a concentric series of radial slots, a plurality of segmental sections interposed between the main and auxiliary disks, and means extending through the slot of the auxiliary disk and having connection with each of the segmental sections for loosely connecting the sections between said disks.

4. A closure for receptacles embodying a main disk, an auxiliary disk arranged above and in spaced relation with the main disk and detachably connected thereto and provided with a concentric series of radial slots, a plurality of segmental sections interposed between the main and auxiliary disks, means extending through the slot of the auxiliary disk and having connection with each of the segmental sections for loosely connecting the sections between said disks, and means having connection with the segmental disks for causing the expansion and contraction thereof.

In testimony whereof I affix my signature in presence of two witnesses.

GEORGE ENTWISTLE.
